UNITED STATES PATENT OFFICE.

WALTER REUSCH, OF NEW YORK, N. Y., ASSIGNOR TO ELECTRIC SEALING MACHINE CORPORATION, OF NEW YORK, N. Y., A CORPORATION OF NEW YORK.

ELECTRIC SEALING DEVICE.

Application filed February 15, 1921, Serial No. 445,248. Renewed January 2, 1923.

To all whom it may concern:

Be it known that I, WALTER REUSCH, a citizen of the United States, and a resident of the city and State of New York, have invented certain new and useful Improvements in Electric Sealing Devices, of which the following is a specification.

My invention relates to a mechanism for applying sealing wax or a similar substance to envelopes, packages and the like and for impressing on said substances, while still in a plastic state a seal by means of a suitable die. The object of this device is to provide a hand operated mechanism of simple construction, electrically heated to bring the sealing wax into a plastic condition and a seal carrying medium also mechanically operated which shall be sufficiently cooled by the presence of a cooling medium such as ice or cold water so as to avoid adhesion of the sealing wax to the seal when the seal impression is being made. In the accompanying drawings, forming part of this specification, I have illustrated a preferred embodiment of my present invention. Fig. 1 is a front elevation of the electric sealing device, and Fig. 2 is a side elevation with parts broken away.

My improved seal press comprises a main metallic frame A with a base 3 which may be perforated as at 4, two standards 5 and 6 connected by a transverse top member 7, and a handle 11 mounted thereon. This handle is provided with a tubular internal recess 11^a to receive, for sliding engagement the upper end of a guide rod or piston 9, about which a coiled spring 10 is provided to exert upward tension against the handle 11. The recess 11^a is of sufficient depth to permit of vertical movement of the handle relative to the guide rod 9 to permit of the depression of the spring 10. The pair of standards 5 and 6 on their inner sides also support a sliding frame B, comprising two arms 13 and 14 and a transverse top member 15, the arms 13 and 14 being parallel with one another and parallel with the standards 5 and 6. These carriers are provided to support a swinging cup 16 by means of a pivoted frame 17 which comprises two vertical oppositely located members 18 and 19 and a transverse cross member 20 upon which the cup is secured as by a screw 21.

To effect the swinging movement of the frame 17 and its cup 16 I provide arms 18

and 19 of the frame 17 each with a pin 22 and a pin 23 secured on each of the arms 13 and 14 and projecting through holes in arms 18 and 19. These pins when the cup is in its lower position are substantially superposed and slide in the vertical portion of a slot 24 provided in each of the vertical standards 5 and 6 of the main frame A. Toward their upper ends the slots 24 are curved as shown at 25 and it will be observed that when the cup 16 and its arms 18 and 19 are in their vertical or lower position for operative use in making the seal imprint the two pairs of pins 22 and 23 will be located in the vertical portion of the slot 24, while when the cup and its arms are in inoperative or raised position the pivot pin (or lower pin) 23 will have been moved, as hereinafter described, upwardly in the vertical slot 24 and the upper pin 22 will have entered into the curved portion 25 of the slot 24, the tilting or swinging of the cup being effected by such slot curvature.

Between the pair of standards 5 and 6 a sealing wax receptacle or cup 26 is fixedly secured to such standards, at either side, by means such as a screw 27. This cup 26 may be made cone shaped, of copper or any other desired metal and has at its lower end an outlet 28 having a plug or valve 29 from which a rod 30 extends upwardly through the interior of the cup for the purpose of opening or closing said outlet by means of a spring-pressed operating lever 31 pivotally mounted on the top of frame A, said lever having handle 32 to which the rod 30 is connected. The handle or knob 11 surrounding the mechanism above described carries a pair of laterally arranged rods 33 extending downwardly and passing through perforations in the transverse top member 7 of the frame A, and the lever 31. These rods 33 are secured to the transverse top member of the inner sliding frame B in any desired manner.

Having reference to the sealing wax cup 26 it will be noted that the wall of the receptacle preferably contains an electric heating element of any approved construction, to which current is supplied by means of wires 34, extending through suitable holes 35 and any connector plug of well known character. It will be noted also that the swinging cup 16 is provided with a cap 37 having an inlet opening 38 and a screw 39 for clos-

ing the same. At the outer side of the bottom of this cup the desired seal is secured as by soldering the same thereto, although the same may be applied in any other desired manner, as by screwing the same thereon.

I shall now describe the operation of my construction:

The inner frame B and the arms 33 and handle 11 connected thereto are maintained in inactive or upper position as shown in full lines under the tension of the spring 10. In this upper position the pin 22 is maintained in the curved portion 25 of the slot 24 while the lower pin 23 is maintained in the vertical portion of said slot. In this position the swinging cup 16 is in tilted position and out of the path of the outlet 28 of the wax cup 26. In order to supply the requisite amount of sealing wax (which previously has been heated in the cup by the electrical heating element) the handle 32 is depressed thus raising through the spring pressed lever 31 the outlet valve rod 30 and raising the plug or valve 29, whereupon the wax will drop upon the article to be sealed. When pressure on the knob 32 is released the plug will again become seated for closed position. Thereupon the handle 11 and its appurtenant parts are depressed whereby the pivoted swinging frame 17 is brought vertically above the wax deposited and directly beneath the wax cup 26. It will be understood that in this position the pins at 22 and 23 are both in the vertical portion of the slot 24. The continued downward pressure will carry the die or seal 37 forming the bottom of the cup 16 into pressing contact with the wax deposited which is in a more or less viscous or plastic state. Upon release of pressure on the handle 11 the cup will again assume its inoperative or tilted position. The presence in the cup 16 of either ice or cold water prevents the seal 37 from becoming unduly heated whereby the adhesion of the sealing wax thereto is completely avoided. It has been found that several hundred impressions could be made without this adhesion and that although the seal or die had been repeatedly carried into contact with the heated wax the water in the cup remained relatively cool, at least sufficiently so to overcome the objectionable adhesion of the wax to the seal.

55 I claim:

1. A device of the character described, comprising a frame, a receptacle rigidly secured to said frame and having an outlet, a valve for normally closing said outlet, a receptacle adapted to contain a cooling medium carrying a die, said receptacle and die being movably supported on said frame, means for opening said outlet, and means for moving said die to a position in which

it will make an impression on material previously delivered from said outlet. 65

2. A device of the character described, comprising a frame, a receptacle rigidly secured to said frame and having an outlet, a valve for normally closing said outlet, a carrier movable lengthwise of said frame, a swinging frame connected with said carrier, a receptacle adapted to contain a cooling medium carried by said swinging frame, a die carried by said receptacle, means for 70 opening said outlet, and means for moving said swinging frame and causing the die to make an impression on material previously delivered from said outlet.

3. A device of the character described, comprising a frame, a receptacle rigidly secured to said frame and having an outlet for delivering material to an object placed under said frame, a valve controlling said outlet, means for operating said valve, a receptacle adapted to contain a cooling medium, a die carried by said receptacle, the receptacle and die being so mounted that normally they will be clear of the path of the material issuing from said outlet, but 85 that they can be moved to a position in contact with the material previously delivered from said outlet, so as to make an impression thereon.

4. A device of the character described, comprising a frame provided with an upright slot and with a curved slot connected with said upright slot at its upper end, a receptacle rigidly secured to said frame and having an outlet, a valve for normally closing said outlet, means for opening said outlet, a receptacle holder adapted to contain a cooling medium, a die carried by said receptacle said receptacle and die being movable with respect to the frame and provided with pins adapted to move in said upright slot, one of said pins being also adapted to move in said curved slot, so as to swing the receptacle with respect to said frame, and means for moving said holder and bringing the die into contact with material previously delivered from said outlet, so as to make an impression thereon. 100 105 110

5. A device of the character described, comprising a frame, a receptacle rigidly secured to said frame and having an outlet, a valve for normally closing said outlet, a receptacle adapted to contain a cooling medium, a die carried thereby both movably supported on said frame, means for opening the outlet, and means for swinging the receptacle from its inoperative position to a position in which its die makes an impression on material previously delivered from said outlet. 115 120 125

In witness whereof I have hereunto set my hand this 10th day of February, 1921.

WALTER REUSCH.
